CLAIM

The ornamental design for a pump case as shown and described.

DESCRIPTION

FIG. 1 is a front isometric view of a pump case according to the present invention.

FIG. 2 is a bottom isometric view of the pump case of FIG. 1.

FIG. 3 is a front elevational view of the pump case of FIG. 1.

FIG. 4 is a rear elevational view of the pump case of FIG. 1.

FIG. 5 is a left side elevational view of the pump case of FIG. 1.

FIG. 6 is a right side elevational view of the pump case of FIG. 1.

FIG. 7 is a top plan view of the pump case of FIG. 1; and, FIG. 8 is a bottom plan view of the pump case of FIG. 1. The broken lines in the drawings are for the purpose of illustrating portions of the pump case that form no part of the claimed design.
